UNITED STATES PATENT OFFICE.

GEORGE B. WEST, OF LESTER TOWNSHIP, BLACK HAWK COUNTY, IOWA.

SHOCKER.

Application filed January 2, 1926. Serial No. 78,922.

This invention relates to shock formers of the type which is attached to binder frames.

The primary object of this invention is the provision of an improved shock former for forming shocks from bundles which are received from a binder.

Another object of my invention is the provision of an improved bundle receiving and packing means for a shock former.

10 Another and further object of my invention is an improved shock holder for such a machine.

Another and still further object of my invention is the provision of an improved dumping mechanism.

Another and still further object of my invention is the provision of a shock former having a receptacle having a portion which moves to the rear when the shock is being deposited upon the ground.

Other and further objects will be apparent, to one skilled in the art, from a reading of the specification and claims.

Referring to the drawing wherein I have illustrated a preferred embodiment of my invention,

Fig. 1 is a front view of my invention showing its relation to the side of the binder.

Fig. 2 is a side elevation of the main parts of my improved shocker which discloses the construction of the main working parts thereof.

Fig. 3 is a rear view of my improved shocker showing the shock dumping mechanism.

Figs. 4 to 8 are views of the details of the mechanism.

In certain of the figures, I have omitted the showing of certain details in order to make the disclosure readily understandable.

It is to be understood that the form of my invention, herein illustrated, is intended to be attached to the right hand side of a binder having a right hand bundle-delivery.

45 The structure, briefly described, comprises a frame work having two parallel valleys into which the bundles are dropped alternately from the binder, a means for packing the bundles into the dumping receptacle and 50 means for quickly dumping the receptacle when it is full, at the same time swinging the

walls of the latter to the rear to insure the delivery of the shock to the ground and maintaining the bundles in an upright position.

Like reference characters refer to the same 55 or similar parts throughout the figures of the drawing.

The main frame consists of a U-shaped frame which I have designated 10, uprights 11 extending therefrom and an upper frame 12 supported at the top of the uprights. The sill is attached to the binder frame by means of extensions 13 attached thereto, which extensions are adjustably connected to extensions 14 from the binder frame, as at 15. 60

After the binding operation, of the binder, takes place in a well known manner, the bundles are delivered by the discharge arm 20 from the binder to the shock former. The receiving portion of the latter comprises two 70 valleys, the valley 21 being adjacent the discharge from the binder and the valley 22 being farthest therefrom. These valleys 21 and 22 are arranged lengthwise with the line of travel of the machine and are separated by an apron 23 which is pivoted on a line which divides the two valleys one from the other and controls the delivery of the bundles to the valleys of the shock former. When the apron 23 is raised, the bundles will be delivered to 80 the nearest or left hand valley 21. When the apron 23 is in lowered position, it serves as a support for the bundles and receives them and delivers them to the right hand or farthest valley 22. The apron may be constructed of 85 metal, wood or any suitable material.

Each valley is provided with a packer. I have designated these packers as 24 and 25, respectively. These packers 24, 25, located respectively in the valleys 21, 22, are of such 90 shape and size that they will substantially equal in area the cross section of the valley, with sufficient clearance, however, to prevent clogging which might be caused by the edge of a packer being too close to the valley wall. 95 The packer 24 is mounted on a support 26 which is in turn carried by two chains 27, 28 extending, respectively, along the inside and outside of the valley 21 and at the floor level thereof, the upper reach of each chain being 100 above the floor level and the lower reach below thereof.

These chains 27 and 28 are mounted on idler sprockets, as the sprocket 29 at the rear of the valley, and at the forward end are supported by gears 30 supported on and keyed to the shaft 31. The shaft 31 is provided at its inner end with a bevel pinion 32 which meshes with a bevel gear 33.

Similarly the packer 25 is mounted on a support 34 which is carried by chains similar in construction to the chain 27, which chains are supported at the front end through the sprockets 35 by the shaft 36. The shaft 36 carries, at its inner end, a bevel gear 37 which is geared to the bevel gear 33, already mentioned. It will be noted that since the gears 32 and 37 are in mesh with the bevel gear 33 on opposite sides, any rotary movement of the gear 33, will cause rotation of the gears 32 and 37 in opposite directions. It will thus be seen that the packers will be moved in opposite directions by a rotation of the gear 33.

On the same shaft with the gear 33, and keyed thereto, is a bevel pinion 38 which is rotated by a segmental gear 39 mounted to rotate about the axle 40 attached to the frame 41 of the partition between the valleys. A rack 42 is in operative engagement with the segmental gear 39 and has a geared bar 43 at its opposite end. This geared bar has an outer guide frame 44 integral therewith. There is sufficient space between the frame 44 and the bar 43, to permit the relative passage of the gear 45 which is mounted on the shaft 46 the latter of which, is mounted adjacent the side of the main frame and extends in a fore and aft direction and while rotatably journaled, maintains its axis in a fixed position relative to the main frame. On the shaft 46 is mounted a sprocket 47 which is similar in size to a sprocket 48 and is driven by a chain 49 connecting the two together. The sprocket 48 is driven from the power chain 50 of the binder in a manner to be described.

Connected to one end of the rack 42 is a flexible cord member 51 which passes over the pulley 52 and the pulley 52' and is connected to the apron 23 as at 53. The connection of the flexible cord member 51 to the rack 42 is at such a place that when the rack 42 is at its position farthest to the right in Fig. 1, the apron 23 will be in a raised position and when the rack 42 is farthest to the left as viewed in Fig. 1, the apron 23 will be in lowered position to direct the bundles to the outside or right hand valley 22.

The operation of the discharge arm 20 is so correlated with the operation of the rack bar 42, that a bundle is delivered to the valley 22 each time the rack bar 42 is at its right hand position and each time it is at its left hand position, a bundle will be delivered to the valley 21. It will thus be clear that by the operation of the shaft 46, the gear 45

meshing with the geared bar 43, moves the same with the bar 42 alternately to the right and left, moving the segmental gear 39 to the right and left and consequently alternately revolving the gear 33 in opposite directions with a resultant moving of the packers 24, 25 in opposite directions alternately as already described.

Rearward of the respective valleys, 21, 22 are shock forming chambers of sufficient size to receive four bundles each. These chambers are formed of side members only, the front being open to receive the bundles from the valleys and the rear ends being open to discharge the bundles comprising the shock.

The two inner walls 60, 61 of these chambers are pivoted together at their upper edges, the lower edges being separated to cause the bundles of the two chambers to lean toward each other in order to be in this position when deposited upon the ground each row of bundles thus forming a support for the other. The walls 60, 61 are supported by means of hangers 62, 63 which are respectively suspended from shafts 64, 65 supported from the frame members 12. The hanger 63 performs the function of a lever since between the supported and supporting ends thereof, is a shaft to which is attached a pitman 66 which at its forward end is connected to a crank 67 of the crank shaft 68. On the crank shaft 68 is keyed a sprocket wheel 69 which is connected by a chain 70 to another sprocket wheel 71 which is keyed on the shaft 72. At one end of the shaft 72 is a bevel pinion 73 which meshes with a bevel pinion 74 mounted to rotate with the shaft 75. At the lower end of the shaft 75 is a bevel pinion 76 which is slidably keyed thereon. When in the lowered position, the pinion 76 engages a bevel pinion 77 which runs continuously. A sprocket 78 is fixed to the pinion 77. A sprocket chain 79 engages the sprocket 78 and also the sprocket 80 arranged to rotate with the sprocket 81 which latter is operated by the drive chain 50 of the binder. The sprocket 48 is integral with the sprocket 78, and is continuously driven thereby.

In position to engage the chain 79 is a large segmental sprocket 82 having teeth on half of its circumference. On the side of the segmental gear is secured a track composed of the outside member 83 and the inside member 84. A lever 85 fulcrumed at 86 carries the roller 87 at its outer end and, at its inner end, is a jaw which engages a collar 88, which is integral with the pinion 76. The ends of the outer and inner tracks 83 and 84 have guiding ends which overlap each other and which are a distance apart to admit of the free but close passage of the roller 87 which latter is mounted in position to always be in contact with one or other of the tracks 83 and 84. When in contact with the inner track, the pinion 76 is in mesh with the pinion 77.

and when the roller is in contact with the outer track 83, the pinion 76 is out of mesh with the pinion 77.

On the same shaft with the segmental sprocket 82 is a segmental ratchet 89 having teeth about one-half of its circumference, eight in number, one tooth corresponding to each sheaf in a complete shock. In position, to act upon the teeth of the segmental ratchet 89 is a sprocket 90 having a single pawl tooth 91 in position to engage one tooth of the ratchet during each revolution. The sprocket 90 is in position to continuously engage the chain 92 which runs on the sprockets 93 and 94, the latter being mounted upon the shaft 95 upon which is also mounted the discharge arm 20 of the binder. The gear ratio between the sprocket 94 and the sprocket 90 is 1 to 1 so that a revolution of the discharge arm causes one revolution of the sprocket 90 and a consequent advance in rotation of the segmental sprocket 82 equal to the angle occupied by one tooth of the ratchet 89. The angular movement of the segmental sprocket 82 caused by the angular travel, which results from eight revolutions of the sprocket 90, is equal to the angle of the outer track 83.

Each time the sprocket 94 with the discharge arm 20 makes eight revolutions, the roller 87 is raised by the inner track 84 which, through the lever 85, causes the gear 76 to mesh with the gear 77 which causes the shaft 75 to be turned. This causes movement to be transmitted through the pinions 74, 73, shaft 72, sprocket 71, chain 70, sprocket 69, crank shaft 68, crank 67, pitman 66 to the lever-hanger 63. As the hanger 63 is pushed rearwardly, the inner walls 60, 61 of the shock receptacle are moved to the rear and upward. At the same time, they are collapsed together, the outer walls move to the rearward and the floor members are released, all in a manner to be described.

By the time the shock receptacle empties its shock, the segmental sprocket 82 will have rotated to a point where it has no further teeth to engage the chain 79. At this point, the roller 87 engages the outer track and the roller end of the lever 85 is lowered to raise the pinion 76 out of engagement with the gear 77. This permits the whole train of gearing which raised the members 60, 61 to be free. The weight of the members 60, 61 causes them to return to the forward position carrying the gearing to a point where it is again ready to operate as soon as the next shock is formed. With the continued discharge of bundles from the binder to the shock former, the segmental sprocket 82 is moved by increments until the teeth of the sprocket again engage the chain 79 with the simultaneous placing of the gear 76 in mesh with the gear 77 for another shock discharging operation.

In order to have a means for setting the sprocket 94 to any particular position rela-

tive to the shaft 95, to facilitate the proper setting of the parts as at the beginning of a day's work, I provide a spring operated clutch member 96 which is keyed to the shaft 95. The sprocket 94 is freely mounted on the shaft and, when in engagement with the clutch member 96, will revolve therewith. The sprocket 94 and the clutch member 96 have cooperating teeth which, while they hold together under normal operation, will slip in case any of the driven gearing becomes stopped from abnormal causes. In such a case, there is no breakage, the teeth permitting the sprocket to stop while the shaft 95 with the clutch member 96 would continue to revolve.

Parallel to the shaft 72 is a shaft 100 supported from the frame members 12. At each end of this shaft 100 is a bevel gear 101 which coacts with bevel gears 102 on the shafts 103. At one end of the shaft 100 is also a sprocket 104 which is driven from the chain 105 and the sprocket 106 which latter rotates with the shaft 72.

Near the bottom of each of the shafts 103 is a crank 107 to which is connected a connecting rod 108, the other end of which is attached to the respective outer walls 109 of the shock delivery receptacle. These walls 109 are preferably made of sheet metal and are supported by rods 110 which are attached at intervals to their lower edges. These rods run on rollers 111, which rollers are journaled upon the frame. Suitable means as springs 115 are provided to hold the walls 109 outwardly. On each of the cranks 107 is provided a wheel 116 against which the wall 109 rests. It is to be noted that the walls 109 of the shock forming receptacle are separate from the outer walls 117 of the respective valleys 21 and 22.

When the shaft 72 revolves, as already described, motion is transmitted through the sprocket 106, chain 105, sprocket 104, shaft 100, gears 101, pinions 102, shafts 103, cranks 107 to the connecting rods 108 which move the walls 109 rearwardly during the dumping operation. After the completion of the dumping operation, the inner walls 60, 61 move forwardly, as already described and the outer walls 109 also move forwardly to their respective initial positions.

At the outer ends of each shaft 64, 65, is a crank 120 to which respective cranks are pivotally attached rods 121 which extend to bell crank levers, upon one end of each of which is a notch 121^a in engagement with the arms 122 which extend from the pivoted receptacle floors 123. It will thus be seen that as soon as the cranks 120 are moved out of alignment with the rods 121, the downward pressure of the shock upon the floors 123 will cause the floor members 123 to fall and dump the bundles thereon. Suitable spring members 123^a are preferably provided of sufficient

strength to lift the floor members 123 when the shock receptacle is empty but ineffective to support the bundles after the disengagement of the notch 121^a with the end of the arm 122, caused by the turning of the cranks 120, as already described.

As previously described, the operation of the crank 67 on the hangers 63, causes the inner walls 60, 61 of the shock former to move 10 to the rear. When this takes place, the two walls, which are hinged together at their upper edges, collapse against each other.

In order to bring about this result, I provide a series of pairs of links 130 pivoted together at their inner ends and having their outer ends pivoted to the walls 60 and 61. These inner ends are connected by a longitudinally extending control bar 131. This bar 131 is connected at its middle by a bar 132 which latter is connected at its upper end by a lever 133. The lever 133 is pivoted at 134 to a block supported in a cut away portion of the inner walls 60, 61. The upper end of the lever 133 is connected to a link 135 25 which extends rearwardly and connects to the frame at 136.

When the inner walls 60, 61 move rearwardly, the fulcrum of the lever 133 moves rearwardly, turning the lower end thereof, 30 relative to the walls 60, 61, about the pivot 134 as a center. This causes the link 132 to be lifted, bending the toggles formed of the links 130 and permitting the walls 60, 61 to collapse. As the walls 60, 61 swing to the 35 rear, the parts return to the former position causing the walls to be again spread apart.

The bundles, when delivered from the binder, are in a horizontal position. I have provided means for straightening the bundles so that when they are in the valleys, they 40 may be in an upright position to be packed and delivered to the ground in a standing position. The numeral 136^a designates the supporting levers which are secured to the inner walls 60 and 61 of the shock forming 45 receptacle. The lower end of these levers 136 are bent and have attached thereto arms 137 which are in position to support the upper ends of the bundles when being delivered.

50 The connections between the levers 136^a and the respective arms 137 are rule joints permitting movement in a rearward direction to permit a bundle to pass when forced by the packers 24 and 25. The springs 136', 55 however, normally tend to hold the arms 137 in positions perpendicular to the line of travel and in substantially horizontal planes. As the packers return to forward positions, the arms 136 also return to their normal positions. The levers 136 are adjustably supported so that they may be swung and raised or lowered to place the parts in proper adjustment.

As already described, the discharge arm 20 60 of the binder is operated whenever a bundle

is ready to be operated. The control for the operation of this arm is a part of the binding mechanism and will not be here described as also hereinbefore stated, the gear 77 is driven continuously as is also the sprocket 70 gear 48 to which it is rigidly attached. Since the sprocket gear 47 is also operated continuously by the chain 49, it only remains to provide mechanism to connect and disconnect the sprocket 47 and its shaft 46, to cause the 75 packer to operate and to cease operating at the end of the performance of its function.

To bring this connection about, I provide means under control of the shaft carrying the discharge arms 20. A rod 137 is eccentrically pivotally connected to the shaft 95 as shown in Fig. 2. This rod 137 is connected at its lower end to an inverted U-shaped shifting device 138. This shifting device straddles a sleeve 139 which is mounted on 80 the shaft 46 and carries the sprocket 47 on its outer surface. The sleeve 139 is provided at its ends with collars 140 and 141, the latter having a sliding connection with the sprocket 47 on the shaft 46. The sprocket 47 85 has a plate which is provided with holes co-operating with the teats 142. The slope of the sides of the teats is such that they will not clutch with their openings unless positively held in cooperation.

The rod 137 has a flange 144 which engages the shifting device 138 when the rod is forced downwardly, the portion of the rod within the shifting device 138 being otherwise free to move vertically.

The chain 49 is provided with two lugs 145 which are oppositely spaced thereon and in position to engage the lug 146 of the shifting device 138, to raise the latter from its lower position.

The number of links of the chain 49 bears the same ratio to the number of teeth of the sprocket 47 as the number of teeth in the rack 43 bears to the number of teeth in the gear 45.

When a bundle is ready to be discharged to the shocker, the discharge arm 20 operates which causes the rod 137 to be placed under compression. The flange 144 engages the shifting device 138, the cam 138^a of which 115 causes the shifting of the sleeve 139 and the engagement of the teats 142 with the corresponding openings of the sprocket 47. As the sleeve 139 is keyed to the shaft 46, the motion of the sprocket 47 is transmitted to the shaft 120 46 therethrough. As the shaft 46 turns, the gear 45 is turned, the rack 43 is moved and the packers alternate, one moving forwardly, the other rearwardly. This operation has already been described.

As the shaft 95 continues to rotate, to complete its cycle, the shifting device 138 does not necessarily disconnect. This is due to the fact that the rod 137 is free to move upwardly as already described. When, however, a lug 130

145 on the chain 49, engages the lug 146 on the shifting device 138, the shifting device is raised. As soon as the cam face 138^a engages the collar 140, the shape of the teats causes them to be disengaged from their openings and thus stopping the operation of the sprocket 47. The parts are now ready for another operation wherein the packer of one side will move to the forward position and 10 the other will move to the rearward position.

Having described the details of construction and operation of these several detailed parts, I will now describe the operation of the device as a whole:—

15 The grain is bundled by the binder in the usual way and the bundles are delivered to the shock forming machine by the arm 20. As already described the alternate bundles will be delivered to the respective valleys 21, 20 22 depending upon whether the apron 23 is in upper or lowered position. While one of the valleys is receiving a bundle, the packer 24 or 25 is packing the previously received bundles toward the rear and into the shock 25 receiving receptacle. The operation of the apron 23 and of the packers 24, 25 is as already described, coordinated with the action of the bundle delivering arm 20. When the required number of bundles are in the receptacle, the gear 82 causes the connection of the gear 76 with the gear 77. This causes the whole dumping mechanism to be placed in action, the inner walls 60, 61 to move rearwardly and collapse, the outer walls 109, are 30 moved rearwardly and the bottoms 123 are caused to be dumped. Due to gravity and springs, as already described, the parts return to their normal position and the shock receptacle is again ready to receive bundles.

40 While I have shown and described one embodiment of my invention, I desire to have it understood that I do not limit myself to the exact showing and that modifications and changes may be made without departing from 45 the spirit of my invention and within the scope of the appended claims.

Having described my invention what I claim is:—

1. A shocker for binders comprising two 50 valleys for receiving the bundles, alternately operated packers for moving the bundles to the rear and means under direct control of the ejecting mechanism of the binder for operating the packers.

55 2. A shocker for binders comprising two valleys for receiving the bundles, alternately operated packers for moving the bundles to the rear and means under direct control of the ejecting mechanism of the binder for operating the packers, said means including an alternately reciprocating rack.

60 3. A shocker for binders comprising two valleys for receiving the bundles, alternately operated packers for moving the bundles to the rear, means for controlling the entry of

bundles, alternately to the valleys, said means including a swinging apron, the apron having a horizontal axis in a line parallel to the valley.

4. A shocker for binders comprising two 70 valleys for receiving the bundles, reciprocating packers moving in the valleys in opposite directions, shock receiving chambers at the rear of the valleys, means for causing deposit of bundles alternately in the valleys 75 and means for releasing the bottoms of the shock receiving chambers when a predetermined number of bundles have been received.

5. A shocker for binders comprising a bundle receiving chamber, means for releasing 80 the bottom thereof when a predetermined number of bundles has been received and means for bodily moving a side of the chamber to the rear as the bundles are dumped to form the shock.

6. A shocker for binders comprising a bundle receiving chamber, means for releasing the bottom thereof when a predetermined number of bundles has been received and means for bodily moving a side of the chamber to the rear and inwardly as the bundles are dumped to form the shock.

7. A shocker for binders comprising a bundle receiving chamber and means for simultaneously releasing the bottom and moving 95 rearwardly opposite sides of the chamber.

8. A shocker for binders comprising two bundle receiving chambers having two adjacent walls inclining toward each other, means for simultaneously releasing the bottoms of the 100 chambers and collapsing the inclined walls toward each other.

9. A shocker for binders comprising two bundle receiving chambers, and means for simultaneously releasing the bottoms of the 105 chambers and moving the outer walls to the rear.

10. A shocker for binders comprising two bundle receiving chambers and means for simultaneously releasing the bottoms of the 110 chambers and moving the outer walls inwardly.

11. A shocker for binders comprising two bundle receiving chambers and means for simultaneously releasing the bottoms of the 115 chambers and moving the outer walls inwardly and rearwardly.

12. A shocker for binders comprising two bundle receiving chambers and means for simultaneously releasing the bottoms of the 120 chambers and moving the outer and inner walls of both chambers rearwardly.

13. A shocker for binders comprising two bundle receiving chambers having two adjacent walls inclining toward each other, and 125 means for simultaneously releasing the bottoms of the chambers, collapsing the inner inclined walls toward each other and moving the outer walls inwardly.

14. A shocker for binders comprising two 130

bundle receiving chambers having two adjacent walls inclining toward each other and means for simultaneously releasing the bottoms of the chambers, collapsing the inner 5 adjacent walls toward each other, moving the outer walls inwardly and moving the outer and inner walls rearwardly.

15. A shocker for binders comprising a valley for receiving bundles from the binder,

a packer in the valley, means in the path of 10 the bundles for turning the same from horizontal position to vertical position as they enter the valley and a pivoted resilient yieldable device for holding the means in position.

In testimony whereof I hereunto affix my 15 signature.

GEORGE B. WEST.
